UNITED STATES PATENT OFFICE.

JOSEPH E. WILKISON, OF WELLSVILLE, OHIO, ASSIGNOR OF ONE-HALF TO
S. M. FERGUSON, OF EAST LIVERPOOL, OHIO.

PIPE-WRENCH.

SPECIFICATION forming part of Letters Patent No. 678,809, dated July 16, 1901.

Application filed December 31, 1900. Serial No. 41,720. (No model.)

To all whom it may concern:

Be it known that I, JOSEPH E. WILKISON, a citizen of the United States, residing at Wellsville, in the county of Columbiana and 5 State of Ohio, have invented a new and useful Pipe-Wrench, of which the following is a specification.

My invention is designed to form a simple, cheap, durable, and easily-operated wrench, 10 and has for its object to so construct the same that very few parts shall be used in its construction, thereby lessening its liability of getting out of order, but at the same time keeping in view the form of wrench to obtain 15 the best results.

A further object of my invention is to so arrange the handle, stock, and bits as to enable the operator to secure the greatest distance of "swing" when working upon radiators or pipes that are closely connected or 20 in such positions that other wrenches have proved ineffectual even when the operator has secured the desired "grip" upon the pipe.

These and various other objects and advantages of my invention will appear in the following specification, reference being had to the drawings forming part thereof, in which—

Figure 1 is a perspective view of my improved wrench, showing the jaws gripped 30 upon a pipe. Fig. 2 is a longitudinal section of the same, the handle being shown in elevation; and Figs. 3, 4, and 5 are details of the several parts detached.

In the drawings, A represents the handle 35 of any suitable length and having at one end a head B, one side of which terminates in a claw B' for engagement with a jaw or stock, and the opposite side of said head terminating in a lug B², having a hole through which 40 passes a bolt C, that securely holds a swinging jaw D to the lug. This jaw D has one end bifurcated, forming ears d, which straddle the lug B², and through which passes the bolt C, thereby forming a swinging jaw that 45 is at all times held in place. Upon the outer surface of the lug B² and formed integral therewith is an extension b, forming a stop to limit the outward movement of the jaw.

The jaw D has a semicircular recess d' in 50 its inner face, in which is firmly held a semicircular bit E, made of tempered steel and having its face serrated, as shown. Upon

the outer end of the jaw is securely riveted a yoke or clevis D', into which is designed to fit the outer end of a removable jaw F, whose 55 inner end is bifurcated, forming ears f f, made to straddle the claw B' to prevent any sidewise movement of the jaw F when the wrench is in operation. The surface of the jaw between and immediately in rear of the 60 ends of the ears f is made of a less thickness than the ears and has its outer surface rounded to form a cam f', upon which the claw B' engages to bind the jaws F and D together. The jaw F is also fitted with a bit-section G, 65 similar in construction and arrangement to the bit E.

The operation of my improved wrench is as follows: When a pipe, for instance, is to be turned, the jaw D is put under the pipe and 70 the end of the jaw F inserted in the clevis D', the bifurcated end dropped down over the claw B', the handle in the meantime being turned in such position as to allow the cam portion f' of the jaw to escape the point of 75 the claw. Then by raising the handle the claw engages the cam, which firmly closes the jaws together and upon the pipe, when by a further movement of the handle the pipe is easily turned.

I may state that the claw has its face that engages the cam tempered to avoid wear.

From the foregoing it will be seen that only the amount of pressure is put upon the pipe that is absolutely necessary to secure a tight 85 grip and when that is attained the further movement of the handle will cause the pipe to turn.

My wrench may be fitted to any size pipe by using a removable jaw having a larger or 90 smaller bit-section, as the case may require, thus avoiding the necessity of having several sizes of wrenches.

Having thus fully described my invention, what I claim as new, and desire to secure by 95 Letters Patent of the United States, is—

1. A wrench comprising a handle, a swinging jaw held thereto, a clevis formed on the free end of said jaw and a removable jaw having one end fitting loosely in said clevis and 100 its other end engaged by the handle to close it, substantially as shown and described.

2. In a wrench, the combination of a handle having an enlarged head on one end there-

of, one side of the head terminating in a lug, the opposite side terminating in a claw, a jaw pivoted at one end to the lug and having its opposite end formed with a yoke, a removable 5 jaw held at one end in said yoke and having its opposite end bifurcated to straddle the claw, and adapted to be engaged thereby, substantially as shown and described.

3. In a wrench, the combination of a handle provided with a claw, a jaw having ears 10 at one end between which the handle is piv-

oted, and at its other end with a yoke, and a removable jaw having one end loosely fitting in the said yoke and provided at its other end with ears and between said ears with a 15 cam-surface adapted to be engaged by the claw of the handle, as set forth.

JOSEPH E. WILKISON.
